UNITED STATES PATENT OFFICE.

BERNARD SCHEINKMAN, OF NEW YORK, N. Y.

DESIGN FOR A SURGEON'S INSTRUMENT.

SPECIFICATION forming part of Design No. 27,065, dated May 18, 1897.

Application filed February 27, 1897. Serial No. 625,418. Term of patent 14 years.

To all whom it may concern:

Be it known that I, BERNARD SCHEINKMAN, a citizen of the United States, residing at New York, in the county of New York and State 5 of New York, have invented and produced a new and original Design for a Surgical Implement; and I do hereby declare the following to be a full, clear, and exact description of the same, reference being had to the accompanying figures of the drawings, forming a part thereof.

Figure 1 is a view in elevation, showing one side of my design for a surgical implement. Fig. 2 is a horizontal sectional view of Fig. 1, 15 the plane of the section being indicated by dotted lines on said figure. Fig. 3 is a cross-sectional view of Fig. 1, taken midway of the ends.

Like letters of reference refer to like parts 20 in the several figures.

The leading feature of my design consists of a body of substantially tubular or hollow cylindrical shape and configuration and open at both ends. One of said openings is substantially bell-mouthed or funnel-shaped, and the other at its edges lying in a slightly-curved surface or plane substantially oblique 25 to the longitudinal axis of the body.

Referring to the drawings, A is the tubular 30 or hollow cylindrical body of the appliance; C, the bell-mouthed or funnel-shaped opening; D, the opening at the opposite end, the edges of said opening lying substantially in

a slightly-curved surface or plane taken approximately oblique to the longitudinal axis 35 of the body. From E to F the exterior outline is on a reverse curve or of ogee shape, as shown. The outline from G to H is quite like that from E to F, except that the curvature is less pronounced. The longitudinal curves 40 of the sides are clearly indicated in Fig. 2.

The shape of the longitudinal passage corresponds closely to the external configuration of the body, as indicated in the cross-sectional view. However, owing to the crescent shape 45 of the right and left hand walls I I, the diameter of the walls being gradually decreased in each direction from I I to J and B, the form of the internal sectional opening is slightly less elliptical than the external circumference 50 of the body. The walls of the body may be separated or open on the line B and the edges lapped one over the other, as shown.

The general shape and configuration of the appliance, both externally and internally and 55 at the ends, are clearly indicated by the several figures of the drawings.

What I claim is—

The design for a surgical implement substantially as herein shown and described. 60

In testimony whereof I affix my signature in presence of two witnesses.

BERNARD SCHEINKMAN.
